DESIGN FOR A FIELD GLASS OR SIMILAR ARTICLE

Cressy A. Mowrey, Elmira, N. Y.

Application August 1, 1940, Serial No. 94,118

Term of patent 7 years

To all whom it may concern:

Be it known that I, Cressy A. Mowrey, a citizen of the United States, residing at Elmira, in the county of Chemung and State of New York, have invented a new, original, and ornamental Design for a Field Glass or Similar Article, of which the following is a specification, reference being had to the accompanying drawing, forming part thereof.

Figure 1 is a side view in elevation of a field

glass or similar article showing my new design; and

Figure 2 is a plan view of the focusing wheel shown in full lines in Figure 1.

The essential features of my design reside in the parts shown in full lines.

I claim:

The ornamental design for a field glass or similar article, substantially as shown and described.

CRESSY A. MOWREY.
